UNITED STATES PATENT OFFICE

100,724

DESIGN FOR A FLOOR BRUSH

Louis F. Strassheim, Merrill, Wis., assignor to
A. Laitner & Sons, Detroit, Mich., a firm com-
posed of Emma R. Laitner, Edward A. Laitner,
and Walter C. Laitner

Application May 21, 1936, Serial No. 62,758

Term of patent 14 years

To all whom it may concern:

Be it known that I, Louis F. Strassheim, a citizen of the United States of America, residing at Merrill, in the county of Lincoln and State of Wisconsin, have invented a certain new, original, and ornamental Design for a Floor Brush, of which the following is a specification, reference being had therein to the accompanying drawing forming a part thereof, in which

Figure 1 is a perspective view of a floor brush showing my new design;

Figure 2 a side elevation thereof;

Figure 3 a plan view thereof;

Figure 4 an end elevation; and

Figure 5 a sectional view thereof on the line 5—5 of Figure 3.

The characteristic features of my design reside in a brush head of uniform thickness throughout its length, the sides thereof converging slightly from the middle towards the ends, the ends being flat.

The head of the brush is further characterized by a raised panel extending centrally thereof, the sides of said panel converging from the middle towards the ends and meeting a short distance from the ends of said brush head.

I claim:

The ornamental design for a floor brush, substantially as shown and described.

LOUIS F. STRASSHEIM.
